THERMIONIC AMPLIFIER

Robert B. Dome, Bridgeport, Conn., assignor to
 General Electric Company, a corporation of
 New York

Application May 29, 1940, Serial No. 337,841

10 Claims. (Cl. 179—171)

My invention relates to a thermionic amplifier and particularly to an amplitude limiting circuit for substantially removing amplitude modulation from high frequency oscillations translated therethrough while reproducing the frequency characteristics thereof with fidelity.

While it is to be understood that my invention is not limited thereto, it will be apparent to those skilled in the art that an amplifier possessing such characteristics has particular utility in phase or frequency modulation systems. In these systems, as is well known, intelligence is communicated by varying the phase, or frequency, of carrier waves in accordance with the signals to be conveyed, rather than by varying the amplitude thereof as in the conventional amplitude modulation systems.

During the transmission of phase or frequency modulated waves some amplitude modulation is almost invariably introduced. This may be caused by "noise" transients, including both man-made interference from ignition systems or other electrical apparatus, and natural atmospheric "static"; or it may be due to irregularities in the transmission circuits themselves or in the medium through which the waves are propagated. Unless this amplitude modulation is removed, the received signal will suffer distortion and the full advantages of phase or frequency modulation will not be realized, as is understood in the art.

It is therefore an object of my invention to provide an improved amplitude limiting circuit for substantially removing amplitude modulation from high frequency oscillations and which is particularly, though not necessarily, adapted for use in a phase or frequency modulation transmission system.

A further object of my invention is to provide an improved translating circuit for limiting the amplitude of translated oscillations to a substantially constant value irrespective of the amplitude of the envelope of the applied oscillations, while reproducing the frequency characteristics thereof faithfully.

Still another and more specific object of my invention is to utilize the inherent capabilities of a self-biased thermionic amplifier to provide a partially effective amplitude limiting action and to provide means for automatically varying the electrical characteristics thereof in accordance with amplitude fluctuations in the average value of the self bias so as to effect a greatly improved limiting action.

The features of my invention which I believe

to be novel are set forth with particularity in the appended claims. My invention itself, however, both as to its organization and method of operation, together with further objects and advantages thereof, may best be understood by reference to the following description taken in connection with the accompanying drawing, in which Fig. 1 diagrammatically represents one form of an amplitude limiting circuit embodying my invention, and Figs. 2 through 8, inclusive, represent curves and graphs helpful in analyzing and understanding the operating characteristics of the circuit of Fig. 1.

Referring now to Fig. 1, the electron discharge device 10 is a multi-electrode tube, illustrated as a pentode having a cathode 11, conventionally represented as of the indirectly heated type, a control grid 12, a screen grid 13, a suppressor grid 14, and an anode 15. Oscillations to be translated by the device 10 are applied to an input circuit extending between control grid 12 and cathode 11 through any suitable coupling means, illustrated as the transformer 16. The secondary winding thereof is tuned substantially to the frequency of the applied oscillations by means of a capacitor 17. The input circuit also serially includes a resistor 18 and a capacitor 19 in shunt thereto. These constitute a grid leak and grid condenser combination for developing a negative self bias potential for the grid 12 in response to received oscillations. As will be explained shortly, in order for an amplitude limiting action to result, it is necessary to proportion the resistor 18 and capacitor 19 so that the negative potential developed thereacross through grid rectification of the applied oscillations at all times equals or exceeds the cutoff bias for the device 10 above a predetermined minimum operating level. In other words, the potential of grid 12 must be maintained sufficiently negative with respect to the cathode 11 so that current flows in the anode circuit only during alternate half cycles of the applied oscillations or fractions thereof.

The anode circuit for the device 10 serially includes a resonant tank circuit comprising the inductance 20 and capacitor 21, a decoupling resistor 22 and a suitable source of anode potential, indicated by the positive and negative terminals 23 and 24. The negative terminal 24 of this source is returned to the grounded cathode 11 in the usual manner and a relatively large bypass capacitor 25 is connected in shunt to the resistor 22 and the source 23, 24. The tank circuit 20, 21 is tuned substantially to the same

frequency as the input tank circuit 16, 17. The anode circuit may be coupled in any suitable manner to a utilization circuit, as for example through the coupling network 26.

The screen grid 13 is connected to a suitable source of potential, as for example the positive terminal 23 of the anode potential source, through a resistor 27. A by-pass capacitor 28 is connected between the screen grid 13 and the cathode 11. As will be explained below, the resistor 27 and the capacitor 28 play a very important part in the improved amplitude limiting action obtained in accordance with my invention. Although the values of resistance and capacitance of these respective elements are not sharply critical, it has been found by actual experiment that materially improved amplitude limiting action in accordance with my invention is achieved when they are properly proportioned with respect to the other constants of the circuit. The proper size for resistor 27 depends on some very complex factors, as will be shown presently, and is most easily ascertained by operating tests. It is a very simple matter to arrive at the proper size through a few trials with resistors of different sizes; or a variable resistor may of course be employed and adjusted for optimum results.

Capacitor 28 is only large enough to provide a low reactance at the frequencies selected by the input and output tank circuits 16, 17 and 20, 21. Thus, the screen grid 13 is maintained substantially at cathode potential for these frequencies, but its potential may vary with respect to cathode 11 at lower frequencies. In general, capacitor 28 must possess a relatively high reactance at any frequencies which are present in the undesired amplitude modulation envelope and which are to be eliminated, as will shortly become apparent.

As previously mentioned, the oscillations, whose envelope is to be limited to a substantially constant amplitude by the circuit of Fig. 1, may be either of substantially constant frequency or modulated in phase or frequency in accordance with signals to be conveyed, such as audio frequency signals, for example. In the latter case the circuits 16, 17 and 20, 21 should be broadly enough tuned to pass all frequencies within the desired signal band with substantially equal efficiency. It is to be understood that these carrier frequencies may be of any values substantially greater than the frequencies which are present in the undesired amplitude fluctuations and which are to be eliminated. In general, the carrier frequencies will be radio frequencies well above the limits of audibility.

For an understanding of the operating characteristics of the circuit of Fig. 1, reference is now made to Figs. 2 through 8, inclusive, in conjunction with the following description.

To simplify this analysis and to facilitate an explanation of the rather complex manner in which the circuit of Fig. 1 is believed to function, a number of assumptions will be made. Assume for the time being that the resistor 27 is short-circuited and that capacitor 28 is made large enough to bypass all frequencies down to a very low value. The screen grid potential is then substantially constant at all times. Assume now that high frequency oscillations, for example, as represented in Fig. 5, are impressed on input transformer 16 and that these are substantially sinusoidal in shape. Through the action of grid leak 18 and condenser 19 peak detection of these

oscillations takes place in a well known manner and a negative grid bias potential substantially proportional to their envelope is thereby developed. Assume further that the amplitude of these oscillations is constant and just sufficient to maintain cutoff bias on the control grid 12. As will be apparent to those skilled in the art, this cutoff bias is dependent upon the screen grid potential, which is assumed constant, and therefore corresponds to a constant negative control grid potential at which no current will flow in the anode circuit.

Under the above assumed conditions, unidirectional pulses of current will flow in the anode circuit during the positive half cycles of the applied oscillations, which reduce the instantaneous grid potential below the cutoff value. Two consecutive pulses are diagrammatically represented by the solid line curve 30 in Fig. 2. This curve represents the variation in anode current along a horizontal time axis. The horizontal portion of the curve 30 extending along the axis BE represents zero anode current, corresponding to a value of grid bias equal to cutoff. The crests 31 of the anode current wave are held to a maximum anode current value corresponding substantially to zero grid bias potential. As is well known, this action is automatically secured by the grid resistor 18 and grid condenser 19, for whenever the grid 12 becomes positive, additional self bias is instantly developed from the flow of grid current. This bias in turn limits the anode current substantially to the zero bias value.

It will be observed that thus far the operation of this circuit resembles that of the ordinary grid leak power detector, with the exception that the self bias developed by grid rectification is deliberately maintained at a high value at least equal to cutoff. The maximum height of the anode current pulses is thus limited substantially to the value AB, as shown in Fig. 2. The crests 31 are limited to the voltage at which grid 12 becomes positive and the valleys are limited to the fixed horizontal line BE by conditions of anode current cutoff.

It will be apparent to those familiar with Fourier's analysis of complex wave forms that the non-sinusoidal wave 30 of Fig. 2 is analyzable into many component sine waves, as well as a direct current component. These sine waves comprise a fundamental wave of the frequency of the oscillations impressed on control grid 12 and many harmonics thereof. It will be recalled that the output tank circuit 20, 21 is tuned substantially to this fundamental frequency. Hence it selects this frequency for transmission to the utilization circuit. The harmonic frequency components are bypassed by capacitor 21.

Under the above assumed conditions, the input signal level is proportional to the maximum value AB of the wave 30 in Fig. 2. If this signal amplitude is selected as a reference level and arbitrarily designated by unity, and if the anode current pulses are assumed to be portions of sine waves, then the maximum amplitude of the fundamental frequency component will theoretically equal .500, by Fourier's analysis. The direct current component will have a coefficient of .318.

Assume that the amplitude of the oscillations impressed on the grid circuit is increased. This may result from amplitude variations in the received signal due to interference, such as "noise," "static," or other factors. For convenience as-

sume for the moment that the maximum amplitude of the waves is exactly doubled. The negative self bias applied to grid 12 will also be substantially doubled. Referring again to Fig. 2, this negative bias will establish a new axis CF for the anode current pulses corresponding to twice the cutoff value. The anode current wave may now be represented by the solid line curve 32. It is seen that anode current can still flow only during the interval AB since dotted line portions 32' of the curve in the interval BC are below the anode current cutoff line BE. This is fixed, since the potential of screen grid 13 remains constant under the assumed conditions. Thus, while the amplitude of the current wave, represented by the distance AB, is the same as before and limited by the same considerations, the anode current flows only during a fraction of positive half cycles. Therefore, these pulses 32 are narrower than the pulses 30 and include a smaller area. Fourier's analysis will immediately show that the coefficient of the fundamental component has been reduced to .387 and the direct current component to .220 due to the increase in input signal amplitude from 1.000 to 2.000, in terms of the arbitrarily selected reference level. Therefore, the fundamental component selected by the output tank circuit has been reduced in amplitude from .500 to .387 and effective limiting has not been accomplished.

The horizontal axis DG in Fig. 2 is representative of conditions where the grid bias is triple the cutoff value, since the distance AD is three times the distance AB. The input signal amplitude is thus 3.000 in terms of the reference level. Under these conditions anode current flows during even a smaller fraction of positive half cycles and the current pulses 33 are still narrower since the dotted portions 33' below cutoff are two-thirds the height of the curve. Fourier's analysis shows that the maximum amplitude of the fundamental frequency component is now further reduced to .330 and the direct current component to .175.

Thus, the above analysis indicates that the magnitude of the envelope of the oscillations selected by the output circuit 20, 21 steadily decreases as the amplitude of signal impressed on the grid 12 increases. This occurs despite the fact that the maximum amplitude of the anode current is substantially constant, since the area of the anode current pulses steadily decreases. The solid line curve 50 of Fig. 3 illustrates this graphically. The ordinates of this curve represent theoretical coefficients of the fundamental frequency component of anode current and the abscissae represent input signal amplitude, both in terms of the arbitrary reference level. The dashed line curve 51 illustrates the variation in the direct current component. I have confirmed the theoretical values of the curves 50 and 51 by experimental tests and have found that they are in close correspondence with actual operating conditions.

The effect of amplitude variations in input signal level is further illustrated in Figs. 5 and 6 which represent oscillograms of signal potential and output current during conditions of a transient increase in signal amplitude, indicated by the positive peaks 40 in Fig. 5. It is seen that the envelope of the output current suffers a corresponding transient decrease, indicated by the negative peaks 41. Thus the amplitude modulation of the received signal has not been eliminated by the circuit.

In accordance with my invention the mutual conductance of the device 10 is caused to vary automatically in accordance with the signal envelope. This I accomplish in the illustrated embodiment of my invention by causing the screen grid potential to vary inversely with the input signal amplitude through the action of resistor 27 and capacitor 28, as will now be explained.

It is a well known characteristic of a pentode 10 that when the control grid potential is varied, both the screen grid and anode currents vary in a similar manner. Thus, if the control grid 12 is made more negative, the current drawn by the screen grid through the series resistor 27 decreases. The potential drop across resistor 27 likewise decreases and the screen grid potential increases, approaching the potential of supply source 23, 24 as the screen current approaches zero. Similarly, if the control grid 12 is driven more positive, the screen grid potential decreases.

As is well understood in the art, varying the screen grid potential varies the mutual conductance of the amplifying device in the same sense. Thus, if the screen grid 13 becomes 25 more positive, the mutual conductance of device 10 is increased. Expressed another way, the anode to cathode resistance of device 10 is decreased and the control grid 12 must reach a more negative potential before anode current 30 cutoff is reached. Thus the anode current cutoff axis BE in Fig. 2 is no longer fixed, but moves downwardly with increased screen grid potentials. Considering the curves 30, 32 and 33 again, the effect is to move the axis BE downwardly with increased input signal amplitudes 35 so that the areas under the current pulses between the crests 31 and the axis BE are roughly constant in all cases. The curve 60 of Fig. 4 is 40 illustrative of the general manner in which the mutual conductance of device 10 varies with the input signal amplitude as a result of the consequent variations in screen grid potential.

As explained previously, capacitor 28 is of 45 relatively small capacity. This is necessary to permit the screen grid potential to follow the input signal envelope up to the highest envelope frequencies to be eliminated from the utilization circuit. As an illustration, if the circuit of Fig. 1 is employed as an amplitude limiter in a receiver of high frequency carrier waves which are 50 frequency modulated by desired audio signals, the time constant of the resistor-capacitor combination 27, 28 must be small enough to permit the screen grid potential to vary at audio frequencies. Thus, undesired fluctuations in the input signal due to "noise" or "static" interference at frequencies within the desired audio frequency signal band, as indicated by the peaks 40 in Fig. 5, for example, produce corresponding fluctuations in the screen grid potential, as 55 illustrated by the curve 43 in Fig. 7. As a result, the negative peaks in the fundamental component of anode current, which appeared so prominently at 41 in Fig. 6 are substantially eliminated and the anode current is of substantially constant amplitude, as indicated in Fig. 8.

If perfect compensation were achieved, the curve 50 in Fig. 3, which represents the variation 70 in the fundamental component of anode current without compensation, would assume the dotted line position 52. That is to say, the anode current would remain absolutely constant irrespective of the input signal envelope as long as its magnitude exceeded the minimum operating signal level. In general, perfect limiting

cannot be attained, but it can be very closely approached. The fundamental component of anode current can be made to assume the position of the curve 53 in Fig. 3, for example. It will be observed that the lefthand portion is slightly under-compensated and the righthand portion slightly over-compensated, since curve 53 is not linear. This non-linearity follows from the fact that the compensating action is the resultant of several independent non-linear variables which are not exactly identical functions of control grid potential. The screen grid current varies approximately as the three-halves power of control grid potential, as is well known, and the anode current varies according to a slightly different law.

By increasing the value of resistor 27 beyond the optimum value, the circuit may be considerably over-compensated, as indicated by the curve 53' in Fig. 3.

It has been found, as a practical matter, that the effectiveness of limiting varies considerably with the nature of the amplitude fluctuations to be eliminated. It is greater for slower variations than for sharply peaked "noise" transients, such as those due to ignition interference. However, even under the most adverse conditions, it is reasonable to expect an increased effectiveness of limiting of at least two-fold when the mutual conductance of device 19 is caused to vary in accordance with the principles of my invention, as hereinbefore explained. The improvement in many cases is very much greater. Thus, in laboratory tests, when the input signal was amplitude modulated 50 per cent by a 400 cycle standard sine wave, an improvement of 45-fold in effectiveness of limiting was obtained when capacitor 28 was reduced to 15 mmf. from 0.1 mfd.

It will be evident that my invention provides an amplitude limiting circuit which is structurally very simple and gives an effective limiting action well within practical tolerances. By way of illustration only, and not by way of limitation, there are listed below values of circuit constants which have been found to be suitable for the circuit of Fig. 1 when employed in a particular superheterodyne frequency modulation receiver. The device 19 was a type 6SJ7 pentode and the circuits 16, 17 and 20, 21 were tuned to the intermediate frequency of about 2.1 megacycles. Other values follow:

Resistor 18=330,000 ohms
 Resistor 22=2,200 ohms
 Resistor 27=100,000 to 300,000 ohms
 Capacitor 19=22 mmf.
 Capacitor 28=15 mmf.
 Capacitor 25=.05 mfd.

The optimum value of resistor 27 was determined by actual tests, as explained. It varied somewhat with the type of interference to be eliminated, though any values within the above range were found to be effective.

It is to be understood that the foregoing analysis is merely illustrative of the fundamental manner in which the circuit of Fig. 1 is believed to operate. Various assumptions as to wave shapes and operating conditions have been made for the purpose of simplifying this explanation. It will be appreciated that these are not essential to the practice of my invention but are merely exemplary. The electrical behavior of the circuit under actual operating conditions is undoubtedly more complex since, as previously pointed out,

the compensating action is the resultant effect produced by several independent non-linear variables. However, the actual results obtainable have demonstrated the effectiveness and practical

utility of my invention.

Although I have illustrated one embodiment of my invention employing a pentode, the mutual conductance of which is controlled by variation of the screen grid potential, other modifications 10 will readily occur to those skilled in the art by which the same results may be achieved. For example, the device 19 may be a screen grid tube rather than pentode, or the device 19 may be a multi-grid tube having the compensating potential applied to some other grid than the screen grid. Therefore, it will be appreciated that I do not wish to be limited to the particular embodiment of my invention disclosed herein since these and other modifications may be made, and 15 I contemplate by the appended claims to cover any such modifications as fall within the true spirit and scope of my invention.

What I claim as new and desire to secure by Letters Patent of the United States is:

25 1. The combination, in an amplitude limiting circuit, of an electron discharge device having grid and anode circuits, means for impressing high frequency oscillations on said grid circuit, means for developing in said grid circuit an average self-bias potential sufficient to maintain said device biased at least to cutoff above a predetermined minimum amplitude of said oscillations at which the limiting action becomes effective, means in said output circuit to select oscillations 30 of the same high frequencies, and means responsive to changes in said bias potential for increasing the mutual conductance of said device when said potential becomes more negative, and vice versa.

40 2. In a circuit for amplifying received high frequency oscillations and for limiting the amplitude thereof, the combination of a thermionic translating device having a cathode, a plurality of control electrodes and an anode, an input circuit between said cathode and one of said control electrodes, means to impress said oscillations on said input circuit, means to develop a bias in said input circuit in response to said oscillations sufficiently great to maintain conditions of anode 45 current cutoff for all amplitudes of said oscillations above a predetermined operating level at which the limiting action becomes effective, an output circuit between said anode and cathode including means for selecting currents of the frequencies of said oscillations, whereby undesired amplitude variations in said oscillations tend to produce amplitude variations in said output currents, and means responsive to variations in said bias for varying the potential of another one of said control electrodes inversely therewith, whereby said current variations are substantially reduced.

55 3. In combination, a thermionic amplifier having grid and anode circuits, means to impress oscillations on said grid circuit, means to produce in said grid circuit a bias potential substantially proportional to the amplitude of said oscillations, said potential being at least sufficient to maintain said amplifier at cutoff above a predetermined minimum operating level, output means in said anode circuit to select currents of said high frequencies whose amplitude tends to vary in accordance with the amplitude of said oscillations, and means to vary the mutual conductance of said amplifier in response to variations in

said bias potential and in a sense to reduce said current variations.

4. In an amplitude limiting circuit, the combination, with a source of oscillations whose envelope is subject to undesired amplitude variations, of a thermionic discharge device having grid and anode circuits, means to impress said oscillations on said grid circuit, means to bias said grid in accordance with the envelope of said oscillations, said bias being sufficient to maintain anode current cutoff above a predetermined minimum operating level at which the limiting action becomes effective, means in said anode circuit to select corresponding oscillations, and means responsive to said undesired variations in the envelope of said first-named oscillations for increasing the mutual conductance of said device when said envelope amplitude increases, and vice versa.

5. In an amplitude limiting circuit, the combination, with a source of oscillatory waves whose envelope is subject to amplitude variations at undesired frequencies, of a thermionic amplifying device comprising a cathode, a control grid, a screen grid and an anode, an input circuit between said control grid and cathode, means for coupling said source to said input circuit, means for biasing said control grid to cutoff in response to said waves comprising a grid leak and grid condenser in said grid circuit, an anode circuit between said anode and cathode tuned to select oscillatory currents corresponding to said waves, a circuit serially including a resistor and a source of positive potential for said screen grid connected between said screen grid and cathode, and a capacitor connected between said screen grid and cathode which has a relatively low reactance at the frequency of said waves and a relatively high reactance at said undesired frequencies.

6. In an amplitude limiting circuit, the combination, with a source of oscillatory waves whose envelope is subject to amplitude variations at undesired frequencies, of a thermionic amplifying device comprising a cathode, a control grid, a screen grid and an anode, an input circuit between said control grid and cathode, means for coupling said source to said input circuit, means for biasing said control grid to cutoff in response to said waves comprising a grid leak and grid condenser in said grid circuit, an anode circuit between said anode and cathode tuned to select oscillatory currents corresponding to said waves, a circuit serially including a resistor and a source of positive potential for said screen grid connected between said screen grid and cathode, and a capacitor connected between said screen grid and cathode, the impedance of said resistor and capacitor in parallel being relatively great at the frequency of said waves and relatively small at said undesired frequencies, whereby the instantaneous potential of said screen grid is caused to vary at said undesired frequencies.

7. In an amplitude limiting circuit, the combination, with a source of oscillatory waves whose envelope is subject to undesired amplitude modulation, of an electron discharge device having a cathode, a plurality of grids and an anode, an input circuit between said cathode and a first one of said grids, means for coupling said source to said circuit, means for biasing said first grid to cutoff in response to said waves comprising a grid leak and grid condenser in said

circuit, an output circuit between said anode and cathode in which pulses of anode current flow during portions of positive half cycles of said oscillatory waves, whereby the envelope of the fundamental frequency component of said anode current pulses and the direct current component thereof tend to vary with said undesired amplitude modulation, and means responsive to said undesired envelope variations for increasing the potential of a second of said grids when said envelope amplitude increases, and vice versa, whereby said variations in said components are substantially reduced.

8. A limiter circuit for amplifying and limiting high frequency waves whose envelope is subject to undesired amplitude modulation at lower frequencies comprising, in combination, a pentode amplifier, an input circuit for coupling said oscillations between the control grid and cathode of said amplifier, a parallel resistance-capacitance combination in said input circuit for effecting grid detection of said oscillations and developing a self bias potential for said grid, said combination being proportioned to maintain said amplifier at cutoff above a predetermined minimum amplitude of said waves, an output circuit between the anode and cathode of said amplifier serially including an output means for selecting waves of said high frequencies and a source of anode potential, a circuit between the screen grid and cathode of said amplifier serially including a resistor and a source of screen grid potential, and a bypass capacitor connected between said screen grid and cathode which has a low reactance for said high frequencies and a high reactance for said undesired frequencies.

9. A limiter circuit for amplifying and limiting high frequency waves whose envelope is subject to undesired amplitude modulation at lower frequencies comprising, in combination, a pentode amplifier, an input circuit for coupling said oscillations between the control grid and cathode of said amplifier, a parallel resistance-capacitance combination in said input circuit for effecting grid detection of said oscillations and developing a self bias potential for said grid, said combination being proportioned to maintain said amplifier at cutoff above a predetermined minimum amplitude of said waves, an output circuit between the anode and cathode of said amplifier serially including an output means for selecting waves of said high frequencies and a source of anode potential, a circuit between the screen grid and cathode of said amplifier serially including a resistor and a source of screen grid potential, and a bypass capacitor connected between said screen grid and cathode, the impedance of said resistor and capacitor in parallel being relatively great at the frequency of said waves and relatively small at said undesired frequencies, whereby the instantaneous potential of said screen grid is caused to vary at said undesired frequencies.

10. An amplitude limiter comprising, in combination, a multi-grid amplifier including a cathode, a control grid, a screen grid and an anode, an input circuit between said cathode and control grid including means to impress high frequency oscillations thereon whose envelope is subject to undesired variations in amplitude and also including self bias means to maintain said amplifier biased at least to cutoff above a predetermined minimum amplitude of said oscillations, a circuit between said anode and

cathode including frequency selective output means to select high frequency currents corresponding to said oscillations, whereby said currents are also subject to undesired variations, and means to cause the potential of said screen grid to vary with respect to said cathode in accordance with frequencies present in said undesired amplitude variations, whereby said varia-

tions are substantially reduced, said last named means comprising a resistor included in the connection to said screen grid and a bypass capacitor connected between said screen grid and cathode having a low reactance for oscillation frequencies and a high reactance for frequencies present in said undesired amplitude variations.

ROBERT B. DOME.
